MOISTURE CONDENSING WATER COLLECTING DEVICE

Filed March 25, 1922

INVENTOR

Charles W. Armbrust

BY his ATTORNEYS

Darby & Darby

UNITED STATES PATENT OFFICE.

CHARLES W. ARMBRUST, OF ALBANY, NEW YORK.

MOISTURE-CONDENSING WATER-COLLECTING DEVICE.

Application filed March 25, 1922. Serial No. 546,654.

This invention relates to water collecting devices and has for its object the provision of a simple means whereby the moisture, from exhaled atmosphere, for example, can be condensed and collected to be saved for further use. The invention is particularly useful in places where water is scarce or where it is not obtainable from customary sources.

10 A further object includes the provision of a simple, compact, economical and efficient moisture-condensing and collecting device, which can be readily applied when necessity requires.

15 Other objects will appear hereinafter, and I attain these objects by the mechanism illustrated in the accompanying drawing of which:

Figure 1 is a view in elevation.

20 Fig. 2 is a section taken on lines 2—2 of Fig. 1, looking in the direction of the arrow.

Fig. 3 is a sectional view of the flutter valve.

25 Fig. 4 is a view on lines 4—4 of Fig. 1 looking in the direction of the arrow.

The same numerals refer to like parts throughout the several views.

In accordance with my invention I provide a condensing container 10 which is provided with supporting straps or belt 11 attached to ears 10' for fastening the container to the body of the user. The container is preferably made from suitable metal, as brass, which is preferably nickelplated or 30 heavily coated and tinned. This container or condenser may be of any suitable size or shape and in the preferred form, as shown, it is disk-shaped, the two disks being united at a median line, as is clearly indicated by 35

40 Fig. 4.

As best shown in Fig. 1, the container is provided with a main receiving tube 12, a relief tube 13 and a saliva collector 14, terminating in a well 15, which is provided 45 with a screw cap 16. The receiving tube is further provided with a main deflecting passage or inner breathing tube 17, which opens directly into the container at 18. This tube may be protected by a saliva deflector and 50 screen 19, for permitting passage therethrough only of the moisture laden breath to the collector or condensing receptacle. An extension 20, of any suitable length, may be provided for the main receiving tube and 55 this extension may be provided with a neck

21, for applying a convenient holder 22 containing a strap 23 for fastening to the head of the wearer. A suitable mouth piece 24 furnishes means for exhaling into the condenser. To protect the device from being contaminated by germ-laden atmosphere or dust entering therein, the mouth piece 24 may be conveniently provided with a suitable stopper 25, which may be safely attached by a chain or cord 26.

The relief tube 13 may be provided with a coupling 27, which may be screw-threaded at 28, for readily detaching, and a ring 29 safely holds the coupling in place. The coupling 27 may be provided with an extension or exhaling tube 30, carrying a supporting neck 31, onto which there is fitted a relief or flutter valve 32. Applied to the neck 31 is a supporting clamp 33, which is fastened on the holding strap 23, by any suitable means, 75 as is a plate 34 and rivets 35, as is best shown in Fig. 2.

The relief or flutter valve may be of any desired shape and size, but in a preferred form, as illustrated, it consists of two lip pieces 36 and 37 which close together against admission of external air, but open upon slight increase of pressure from within. This construction permits exhaled air to be respiration through the mouthpiece 24, thence through the extension tube 20, deflecting tube 17 into the container or condenser, where by condensation it is relieved of practically all its moisture if the temperature of the atmosphere is low enough and thereafter passes out through the relief tube, the exhale tube and the flutter valve to the open atmosphere. By thus passing through the apparatus, as above described, which is by way of illustration, merely, practically all the moisture contained in the exhaled atmosphere or breath is condensed and thus saved and collected in the container whence it may be obtained as desired. The invention is particularly useful in connection with relief 90 expeditions and armies marching through desert territory, or where an army or detachment is cut off from a water-supply. It is also useful on ships in other connections where a supply of water is not available.

100 While I have described a specific embodiment of my invention and a mode of applying the same, I do not thereby desire to be understood as having thus limited myself, as 105 obvious modifications falling wholly within 110

the spirit and scope of my invention will readily suggest themselves to those versed in the art.

What I claim, therefore, as new and useful and of my own invention and desire to secure by Letters Patent is:

1. In a moisture-condensing and water-collecting device, a container provided with an inlet tube and an outlet tube, a deflector tube within one of said tubes, and means attached to said outlet for permitting exhaled air to pass in one direction only.

2. In a moisture-condensing and water-collecting device, a container provided with an inlet and an outlet, tubes connected to said inlet and outlet, a deflector tube within said inlet tube, said deflector tube opening into said container through the walls of said inlet tube, and means on the outlet tube for closing and opening by difference of atmospheric pressure within and without said container.

3. In a moisture-condensing and water-collecting device, a container provided with

an inlet and an outlet, tubes associated with said inlet and outlet, a concentrically located tube within one of said tubes, a well in said container, and an extension on one of said associated tubes reaching into said well.

4. In a moisture-condensing and water-collecting device, a container provided with an inlet and an outlet, tubes associated with said inlet and outlet, a concentrically located tube within one of said tubes, a mouthpiece on one of said tubes, and a valve on the other of said tubes.

5. In a moisture-condensing and water-collecting device, a container provided with an inlet and an outlet, tubes associated with said inlet and outlet, a mouthpiece on one of said tubes for receiving exhaled breath, a deflector tube within one of said tubes, and a flutter valve for permitting expired air to pass out of the container.

In testimony whereof I have hereunto set my hand on this 27th day of January A. D. 1922.

CHARLES W. ARMBRUST.
